UNITED STATES PATENT OFFICE.

FRANCIS G. BATES, OF PHILADELPHIA, PENNSYLVANIA.

STEAM-BOILER FURNACE.

SPECIFICATION forming part of Letters Patent No. 445,419, dated January 27, 1891.

Application filed May 1, 1890. Serial No. 350,153. (No model.)

To all whom it may concern:

Be it known that I, FRANCIS G. BATES, a citizen of the United States, and a resident of Philadelphia, Pennsylvania, have invented 5 certain Improvements in Steam-Boiler Furnaces, of which the following is a specification.

The object of my invention is to so construct a furnace for a steam-boiler, and especially 10 for a boiler of the locomotive type, as to insure the effective combustion of the gases arising from the fuel; and this object I attain in the manner hereinafter set forth, reference being had to the accompanying drawings, in 15 which—

Figure 1 is a longitudinal section of the fire-box of a boiler of the locomotive type, illustrating my invention as applied thereto. Fig. 2 is a sectional plan view of the same on the 20 line 1 2, Fig. 1. Fig. 3 is a transverse section on the line 3 4, Fig. 1; and Figs. 4 to 10 are detached perspective views of the parts comprising a hollow partition forming part of my invention.

In Figs. 1, 2, and 3, A represents the usual 25 water-jacketed casing of the fire-box, B the crown-sheet, and B' the tubes, the rear wall of the fire-box having the usual feed-opening a. There are, however, in my improved furnace two fire-places, arranged one on each 30 side of a hollow partition E, which is by preference composed of slabs of fire-brick or other refractory material constructed and fitted together in the manner hereinafter set forth, 35 this partition being mounted upon water-tubes b, extending from the front to the rear wall of the fire-box. Each fire-place also has a grate composed of similar water-tubes d. The hollow partition E is composed of a top 40 plate D, a bottom plate F, opposite side plates G, a front plate H, and a rear plate J, the top and bottom plates having dovetailed recesses f for the reception of dovetailed projections g upon the side plates and front plate, and the 45 rear plate J having a dovetailed recess h and vertical ribs i, the former for the reception of a dovetailed projection h' on the top plate and the vertical ribs i for bearing against the side plates of the partition and retaining the same 50 laterally in place, the bottom plate F of the partition being also recessed for the reception of the supporting-tubes b, as shown in Fig. 3,

which thus aid in retaining the partition in its proper lateral position. A key-block k is inserted in the recess h above the tongue h', 55 and the rear face of said plate J has recesses m formed therein, so as to provide for the passage of air between the said plate J and the rear wall of the fire-box.

Air enters the hollow partition E through 60 tubes n in the front and rear walls of the fire-box and through openings n' in the front and rear plates of the partition, air also entering the partition through an opening p at the rear end of the bottom plate F. The air heated in 65 the partition is permitted to escape therefrom laterally through openings s in the side plates G and vertically through openings t in the top plate D. Hence as the gases arise from the fuel in each of the side fire-places heated 70 air mingles with said gases, and further supplies of heated air are projected into the gases as they unite over the top of the hollow partition, the consequence being that thorough 75 and effective combustion of gases is insured.

In the upper portion of the fire-box is a deflector M, composed of slabs of fire-brick or other refractory material mounted upon water-tubes w, extending from the front wall of the fire-box rearwardly and upwardly to the 80 crown-sheet B, the purpose of this deflector being to cause the products of combustion to seek the upper rear end of the fire-box before they can pass through the upper portion of said fire-box to the tubes B'. This concentration of the products of combustion in the rear portion of the fire-box insures the effective mingling with the same of the hot air derived from the hollow partition. As the products of combustion sweep rearward in order 85 to pass round the rear end of the deflector M, they are met by further volumes of heated air ascending from the passages m, formed in the front plate J of the partition, so that ample supplies of oxygen are furnished to insure 90 the combustion of all the gases arising from the fuel.

The openings n may, if desired, be provided with suitable dampers to regulate the inlet of air to the hollow partition.

Having thus described my invention, I claim and desire to secure by Letters Patent—

1. The combination, in a fire-box, of the fire-places, located side by side, and the hollow

- partition interposed between said fire-places and extending only part way to the top of the combustion - chamber, said partition having inlets for receiving air and outlets for discharging the heated air into the products of combustion arising from the fire-places, substantially as specified.
2. The combination of the fire-places, located side by side, and the hollow partition interposed between the fire-places and extending only part way to the top of the combustion-chamber, said partition having inlets for the air and side and top outlets therefor, so as to cause the escape of the heated air both laterally and vertically into the products of combustion from the fire-places, substantially as specified.
3. The combination of the fire-places, located side by side, the hollow partition separating the fire-places and having air inlets and out-

lets, and a deflector in the upper portion of the fire-box above said partition, substantially as specified.

4. The combination of the two fire-places, the hollow partition separating the same and having air inlets and outlets, and vertical air-heating passages formed in the front plate of said partition, substantially as specified.

5. The combination of the two fire-places, the hollow partition separating the same and having air inlets and outlets, and water-tubes serving to support said partition, substantially as specified.

In testimony whereof I have signed my name to this specification in the presence of two subscribing witnesses.

FRANCIS G. BATES.
